UNITED STATES PATENT OFFICE.

ALBERT PHILIP SUTER, OF NEW YORK, N. Y.

DESIGN FOR A HAIR ORNAMENT.

SPECIFICATION forming part of Design No. 26,172, dated October 13, 1896.

Application filed September 4, 1896. Serial No. 604,904. Term of patent 14 years.

To all whom it may concern:

Be it known that I, ALBERT PHILIP SUTER, of New York, in the county and State of New York, have invented and produced a new and original Design for a Hair Ornament, of which the following is a full, clear, and exact specification.

Reference is to be had to the accompanying drawings, forming a part of this specification, in which similar characters of reference indicate corresponding parts in both the figures.

Figure 1 is a side elevation of a hair ornament embodying my design, and Fig. 2 is a sectional plan view of the same.

15 The leading feature of the design consists

in a vane having minute filaments A curved outwardly and upwardly from opposite sides of an approximately central stem B. A minor feature of the vane is the S-shaped cross-section shown in Fig. 2.

20

The lower end C of the vane A is made V-shaped and terminates in a pin D.

I claim—

The design for a hair ornament, as herein described.

ALBERT PHILIP SUTER.
